DESIGN FOR A BOARD FOR PLAYING THE GAME OF QUOITS

Edward G. Schumacher, Buffalo, N. Y.

Application April 29, 1938, Serial No. 76,864

Term of patent 7 years

To all whom it may concern:

Be it known that I, Edward G. Schumacher, a citizen of the United States, residing at Buffalo, in the county of Erie and State of New York, have invented a new, original, and ornamental Design for a Board for Playing the Game of Quoits, of which the following is a specification, reference being had to the accompanying drawing, forming part thereof.

In the accompanying drawing:

Fig. 1 is a plan view of the board for playing the game of quoits showing my design.

Fig. 2 is an edge view of the same.

I claim:

The ornamental design for a board for playing the game of quoits, as shown.

EDWARD G. SCHUMACHER.
